Primary Examiner — Terry A Wallace(74) *Attorney, Agent, or Firm* — Knobbe, Martens, Olson & Bear LLP(57) **CLAIM**

The ornamental design for a juicing device, as shown and described.

DESCRIPTION

FIG. 1 is a top, front, left-side perspective view of a juicing device embodying our design;

FIG. 2 is a bottom, rear, right-side perspective view thereof;

FIG. 3 is a front view thereof;

FIG. 4 is a rear view thereof;

FIG. 5 is a right-side view thereof;

FIG. 6 is a left-side view thereof;

FIG. 7 is a top view thereof; and,

FIG. 8 is a bottom view thereof.

All features in broken line form no part of the claimed subject matter.
